GRINDING MACHINERY

Willetts Peaslee and Lester F. Nenninger, Cincinnati, Ohio, assignors to Cincinnati Grinders Incorporated, Cincinnati, Ohio, a corporation of Ohio

Application April 5, 1933, Serial No. 664,571

14 Claims. (Cl. 51—49)

This invention relates to improvements in machine tools and particularly to improvements in grinding machines.

An object of the present invention is the provision of an improved work supporting mechanism for use with grinding machines which are particularly adapted for the grinding of large heavy work pieces.

Another object of the invention is the provision of a mechanism for supporting work pieces in a grinding machine which may be controlled and adjusted from a point remote therefrom.

A further object of the invention is the provision of a journaled rest for use with roll grinding machines that is adapted to be adjusted from the normal operator's control station which is remote from the rest itself.

Other objects and advantages of the present invention should be readily apparent by reference to the following specification considered in conjunction with the accompanying drawings forming a part thereof, and it is to be understood that any modifications may be made in the exact structural details there shown and described, within the scope of the appended claims, without departing from or exceeding the spirit of the invention.

In the drawings:

Figure 1 is a front elevation of a grinding machine embodying the improved journal rest of this invention.

Figure 2 is an enlarged fragmentary sectional view taken on line 2—2 of Figure 1.

Figure 3 is an enlarged fragmentary sectional view taken on line 3—3 of Figure 1.

Figure 4 is a transverse sectional view taken on line 4—4 of Figure 2 and showing the control or operating mechanism.

Figure 5 is a fragmentary transverse sectional view taken on line 5—5 of Figure 2.

Figure 6 is a top plan view of the machine shown in Figure 1.

Figure 7 is a wiring diagram illustrating the electrical circuits utilized in this invention.

Throughout the several views of the drawings similar reference characters are employed to denote the same or similar parts.

In general this invention pertains to a journal rest as employed in roll grinding machines and particularly to such rests when utilized with large or heavy roll grinding machines and is adapted to be adjusted to shift the axis of the work at one end thereof and thereby align said axis with the path of travel of either the work support itself or the grinding wheel. It will,

therefore, be appreciated that even though the invention is shown as utilized with the traveling wheel head type of machine, it can readily be mounted on the standard or conventional type of machine in which there is employed a work supporting table translatable relative to the bed and to a grinding wheel operating on the work on the table. In the past it has been necessary for the operator to adjust the setting of the journal rest manually and to effect said adjustment while in proximity thereto while with this invention the setting of the journal rest may be varied from a position remote from said rest and without the operator leaving his normal station or position.

As seen in Figures 1 and 2, the grinding machine itself comprises a bed 10 mounted on a platform 11, here shown as composed of concrete and formed integral with the normal floor 12, but disposed in a plane below the plane of the floor. Entirely surrounding the platform and formed between the platform and a vertical wall which terminates at the floor level is a channel 13 employed as a tank for the coolant utilized in the operation of the machine. In effect the bed 10 is mounted on an island substantially surrounded by liquid which is the coolant directed against the work and wheel during the grinding operation.

The bed 10 is provided substantially throughout its length with a rearwardly extending projection 14 on which are formed guideways (not shown) for guiding the grinding wheel carriage 15 in its travels lengthwise of the bed. The carriage 15 has journaled therein a spindle 16 to the forward end of which is secured a grinding wheel 17. The wheel 17 and its spindle 16 are rotated at the usual high grinding rate of speed by a prime mover or motor 18 mounted on the upper surface of the carriage 15. The motor 18 is connected with the spindle 16 by a suitable transmission such as belts or gearing enclosed within the guard 19 secured to the carriage 15. Also mounted on the carriage 15 is a stand 20 bearing a seat 21 for the operator whereby the operator is disposed in position to at all times watch the action of the wheel 17 on the work.

The front portion of the bed 10 is formed on its upper surface with a flat guideway 22 and an inverted V-guideway 23 for receiving and aligning the journal rests and tail stock. At the other end the bed is slightly undercut as at 24, see Figure 1, to which is bolted a prime mover 25 coupled with the driving mechanism in the head stock 26. The head stock 26 ter-

minates in a face plate 27 from which projects a center 28 in line with the center 29 of the tail stock 30. The face plate 27 also has projecting from it driving dogs 31 whereby the work 5 is rotated.

As shown in Figure 1, the work is a large roll, the body portion 32 of which is shown in phantom lines and from each end of which projects the journal bearings 33 and 34 shown in heavy 10 or solid lines. The journals 33 and 34 are supported by bearing shoes associated with the journal rests indicated generally in Figure 1 by the numerals 35 and 36. The journal rests are similar in all respects and it is believed that a description of one of them will suffice for the both. 15

Accordingly the journal rest 36 comprises a casting or housing 37 having formed therein at angles to one another bores 38 and 39 respectively receiving bearing shoes 40 and 41. The 20 bearing shoes are adapted to be axially shifted toward the center of the work along lines that intersect on the axis thereof, for which purpose the shoe 40 has rotatably journaled therein a nut 42 while the shoe 41 is formed with rack teeth 43. Meshing with the threads of the nut 42 is a screw 44 journaled intermediate its ends in a housing 45 formed integral with the main housing or casting 37. Secured to the end of the screw 44 and enclosed within the housing 45 is 25 a worm wheel 46 meshing with a worm 47 and constituting a means for holding the screw 44 against rotation when the nut 42 is rotated relative thereto. Integral with and serving as a means for rotating the nut 42 is a hand wheel 30 48 whereby the shoe 40 is axially shifted. 35

The shoe 41 has meshing with its rack teeth 43 a rack pinion 49 keyed or otherwise secured to a stub shaft 50 rotatably journaled in the main housing or casting 37. Also keyed or otherwise secured to the stub shaft 50 is a form wheel 51 meshing with a worm 52 integral with or secured to a vertically extending shaft 53. The shaft 53 is journaled in suitable anti-friction bearings 54 carried by the casting 37 40 as well as in a plain bearing 55 formed in the casting above the shoe 40. The shaft 53 passes through an elongated perforation 56 formed in the bearing shoe 40 and the shaft has secured to it beyond the bearing 55, a hand wheel 57 45 whereby said shaft is actuated and whereby the shoe 41 is manually axially adjusted. 50

From the foregoing it will be noted that the 55 shoes 39 and 40 are manually adjustable axially of themselves toward the axial center of the work for setting up purposes and the like as when initially adjusting the parts to suit a given journal bearing size prior to the grinding of the roll. In practice it frequently happens that the work may be being ground with a slight 60 taper such as a thousandth of an inch or so from one end to the other. This mis-alignment may be corrected by inching, that is slightly shifting the large end of the work toward the grinding wheel, which may be effected by slightly 65 rotating the hand wheel 48 and nut 42. This, of course, would necessitate the operator leaving his station or seat 21 on the grinding wheel carriage and traveling around the machine to the front thereof to accomplish the 70 said adjustment. This it will be appreciated entails a considerable loss of productive time, both on the part of the operator and the machine, since the machine must necessarily remain idle until the operator returns to his seat. 75 By this invention this loss of productive time

is unnecessary and is eliminated, since there is provided means for adjusting the shoe 40 from his normal operating position.

This inching or adjusting means comprises the worm and worm wheel 46 and 47 above referred to, the former being secured to one end of the adjusting screw, while the latter is formed integral with or otherwise secured to a worm shaft 58 rotatably journaled in bearings provided by the housing 45. Keyed or otherwise secured to the shaft 58 is a ratchet 59 having teeth 60 co-operating with a pawl 61. The pawl 61 is pivoted at 62 to a lever 63 loosely journaled on the worm shaft 58. A spring 64 is provided and has one end secured to the lever 63 while the other 10 end is secured to the pawl 61 and acts to hold the nose of the pawl 61 at all times in engagement with the teeth 60 of the ratchet 59. The free end of the lever 63 is connected by a pin and slot connection 65 with the movable core 66 15 of a solenoid 67 secured to an inner wall of the main housing or casting 37. 20

It will be understood that the solenoid 67, its core 66, the lever 63, and ratchet and pawl are so related that a movement of the core 66 will effect a definite advance or rotation of the ratchet 59. This rotation of the ratchet 59 consequently rotates the worm 47 and worm wheel 46 thereby rotating the screw 44 relative to the nut 42 and axially adjusting the position of the shoe 40. In order to insure the rotation of the screw 44 and the nut 42 remaining stationary, a clamping mechanism is provided. This clamping mechanism comprises a clamp pin 68 disposed in an aperture formed in the shoe 40 and contacting on one end with the nut 42. The free end of the clamp pin 68 is beveled to form a cam face 88 which contacts with a co-operating cam face 89 on a push pin 90 disposed in an aperture formed in the shoe 40 40 at right angles to the aperture for the clamp pin 68. The outer end of the push pin aperture is threaded for a clamp screw 91 which has a screw drive slot therein. 35

From the foregoing it will be noted that by 45 screwing the clamp screw 91 inwardly, access to the screw slot being had through the spokes of the handwheel 48, will urge the push pin 90 inwardly and through the co-operating cam faces 89 and 88 will shift the clamp pin 68 outwardly 50 into clamping contact with the nut. 55

The solenoid 67 is, of course, electrically operated and the solenoid therefore includes a push button type of switch whereby it is completed. This push button may be any one of the push 60 buttons 69 carried by a control panel or board on the standard 70 extending upwardly from the grinding wheel carriage and therefore at all times movable with the operator and within his reach without in any wise leaving his normal control station. From this it will be seen that he need only press the desired push button switch for either shifting the right hand end of the work through the journal rest mechanism 36 or the left hand end of the work through the 65 mechanism 35. 70

In order to clamp the journal rests in position, the housing or casting 37 is provided on one side thereof with an ear or lug 71 through which extends a clamping screw 72. The inner end of the clamping screw 72 engages the longer arm 73 of a bell crank 74 pivoted at 75 to the housing or casting 37. The shorter arm 76 of the bell crank 74 is adapted to engage the under surface of a ledge or flange 77 extending inwardly from 75

the front of the bed and which conveniently may be a part of the flat guideway 22.

Upon release of the clamping mechanism the journal rests 35 and 36 may be independently translated together with the mechanism carried thereby relative to the flat and V-guideways 22 and 23. For this purpose there is provided a relatively short shaft 78 journaled in a bearing provided by the housing extension 45. Internally the housing 37 and projecting from one wall thereof is a boss 79 in which is journaled a second short shaft 80. These shafts are connected together by universal joints 81 and 82 and an intermediate shaft 83. Secured to the shaft 80 adjacent the boss 79 is a rack pinion 84 meshing with a rack 85 secured to the flattened apex 86 of the inverted V-guideway 23. The outer end 87 of the shaft 78 is given an angular cross section for the reception of a suitable wrench or the like whereby the jointed shaft may be rotated for correspondingly rotating the rack pinion 84 and traversing the journal rests relative to the bed.

It is believed that the operation of the improved remotely controlled journal rests will be readily understood and that the bearing shoes thereof may be manually adjusted for initially setting up the machine and the like and may be subsequently adjusted from the operator's position for taking care of mis-alignments and the like.

What is claimed is:

1. In a grinding machine of the class described the combination of a bed, a grinding wheel carriage mounted on the bed, an adjustable work support mounted on the bed, means associated with the work support for effecting its adjustment an operator's station on the grinding wheel carriage, and control means operable at the operator's station for actuating the work support adjusting means.

2. In a roll grinder of the class described for grinding rolls which have cylindrical journals projecting therefrom the combination of a bed, journal rests on the bed receiving the journals of the rolls, means associated with the journal rests for effecting an adjustment thereof of a grinding wheel mounted on the bed, and means remote and apart from the journal rests but connected with their adjusting means for operating the journal rest adjustments means for modifying the supporting action thereof.

3. In a roll grinder for grinding rolls from which project journal bearings the combination of a bed, a journal rest mounted on the bed for receiving the journal bearing, a pair of shoes associated with the rest, manual means for shifting the shoes relative to the rest, additional means for further shifting one of said shoes and means remote and apart from the rest for controlling the operation of said additional means.

4. In a roll grinder for grinding rolls from which project journal bearings the combination of a bed, a journal rest mounted on the bed for receiving the journal bearing, a pair of shoes associated with the rest, manual means for shifting the shoes relative to the rest, and means remote from the rest for modifying the position of one of the shoes, said means including electro-magnetic means operatively connected with the shoe, and means remote therefrom for energizing the electro-magnetic means.

5. In a journal rest or support for use with roll grinding machines the combination of a bracket, a pair of shoes mounted in the bracket

for movement relative thereto, manual means for each shoe for independently adjusting the positions thereof, one of said manual means including a nut rotatably carried by the shoe, a screw operatively connected with the nut and journaled in the bracket for independent rotation, and power actuated means for rotating the screw independent of the rotation of the nut.

6. In a journal rest or support for use with roll grinding machines the combination of a bracket, a pair of shoes mounted in the bracket for movement relative thereto, manual means for each shoe for independently adjusting the positions thereof, one of said manual means including a nut rotatably carried by the shoe, a screw operatively connected with the nut and journaled in the bracket for independent rotation, power actuated means for rotating the screw independent of the rotation of the nut, and means locking the nut against rotation to permit rotation of the screw.

7. In a journal rest or support for use with roll grinding machines the combination of a bracket, a pair of shoes mounted in the bracket for movement relative thereto, manual means for each shoe for independently adjusting the positions thereof, one of said manual means including a nut rotatably carried by the shoe, a screw operatively connected with the nut and journaled in the bracket for independent rotation, power actuated means for rotating the screw independent of the rotation of the nut, and means locking the nut against rotation to permit rotation of the screw, said screw rotating means including a worm and worm wheel, a ratchet for rotating the worm, and electro-magnetic means for incrementally rotating the ratchet.

8. In a journal rest or support for use with roll grinding machines the combination of a bracket, a pair of shoes mounted in the bracket for movement relative thereto, manual means for each shoe for independently adjusting the positions thereof, one of said manual means including a nut rotatably carried by the shoe, a screw operatively connected with the nut and journaled in the bracket for independent rotation, power actuated means for rotating the screw independent of the rotation of the nut, and means locking the nut against rotation to permit rotation of the screw, said screw rotating means including a worm and worm wheel, a ratchet for rotating the worm, electro-magnetic means for incrementally rotating the ratchet, and means remote from the journal support for energizing the electro-magnetic means.

9. In a work supporting mechanism for use with machine tool organizations the combination with a bed having formed thereon guideways, of a housing or bracket having cooperating guideways mounted on the bedways, a pair of contact shoes carried by the bracket for movement relative thereto into engagement with the work, manual means for initially adjusting the positions of the shoes, and power means for modifying the position of one of said shoes.

10. In a work supporting mechanism for use with machine tool organizations the combination with a bed having formed thereon guideways, of a housing or bracket having cooperating guideways mounted on the bedways, a pair of contact shoes carried by the bracket for movement relative thereto into engagement

with the work, manual means for initially adjusting the positions of the shoes, power means for modifying the position of one of said shoes, means for clamping the housing to the bed, and 5 means for translating the housing relative to the bed when un-clamped.

11. In a work supporting mechanism for use with machine tool organizations the combination with a bed having formed thereon a flat 10 and a V-guideway, of a housing having cooperating guideways mounted on the bedways, a pair of contact shoes carried by the housing for adjustment relative thereto into engagement with the work, manual means for initially adjusting the positions of the shoes, power means for modifying the position of one of said shoes, and means for rendering the manual means inoperative prior to the operation of the power means.

20 12. In a work supporting mechanism for use with machine tool organizations the combination with a bed having formed thereon a flat and a V-guideway, of a housing having cooperating guideways mounted on the bedways, a 25 pair of contact shoes carried by the housing for adjustment relative thereto into engagement with the work, means carried by the housing for effecting the adjustment of the shoes, a rack secured to one of the bedways, a pinion rotatably mounted on the housing in mesh with the rack, and means extending from the pinion through and beyond the housing for rotating the pinion and translating the housing relative to the bed.

30 35 13. In a work supporting mechanism for use

with machine tool organizations the combination with a bed having formed thereon a flat and a V-guideway, of a housing having cooperating guideways mounted on the bedways, a pair of contact shoes carried by the housing for adjustment relative thereto into engagement with the work, means carried by the housing for effecting the adjustment of the shoes, a rack secured to one of the bedways, a pinion rotatably mounted on the housing in mesh with the rack, means extending from the pinion through and beyond the housing for rotating the pinion and translating the housing relative to the bed, and means for clamping the housing to the bedways.

15 14. In a mechanism of the class described the combination of a bed, a grinding wheel support mounted on said bed, a work support on said bed for supporting a work piece substantially 20 at the terminals thereof, said work piece and grinding wheel having their axes extending in substantially parallel planes, means for axially shifting one of said supports relative to the other, means associated with said work supports 25 for effecting an adjustment of the terminal portion thereof to shift the work toward the grinding wheel to bring the axes of the work and wheel into parallelism, and control means remote and apart from said work support to 30 effect the operation of said adjusting means, said adjusting means being electro-magnetic in nature.

WILLETTS PEASLEE.
